UNITED STATES PATENT OFFICE.

SPENCER OTIS, OF CHICAGO, ILLINOIS.

LOCOMOTIVE BLOW-OFF SYSTEM.

Application filed February 5, 1921. Serial No. 442,847.

To all whom it may concern:

Be it known that I, SPENCER OTIS, a citizen of the United States, residing at Chicago, in the county of Cook and State of Illinois, have invented certain new and useful Improvements in a Locomotive Blow-Off System, of which the following is a specification.

This invention relates to a system by which to blow off steam, water, sludge and the like from steam boilers, and is designed primarily for blowing off locomotive boilers.

The object of the invention is to provide a simple, efficient and inexpensive system which may be arranged for use in situations where it is not desired to save the products blown off but merely to discharge the same under conditions which will not be objectionable in the roundhouse or other place of discharge.

Accordingly, the invention consists in providing a blowoff pipe adapted for convenient connection with the boiler to be blown off, and preferably consisting of a standpipe with a crane extension through which it connects with the boiler, and having its crane extension swiveled so that it can connect with boilers in different situations; said blowoff pipe being connected with a drain through which the products may be discharged; a coldwater pipe discharging into the blowoff pipe in a relation which adapts the cold water to condense steam in the blowoff pipe, and, preferably, a vented steam separator interposed in the drain and through which any uncondensed steam may be discharged in order to prevent injury that might be caused otherwise to a sewer to which the drainage leads.

In the accompanying drawings,—

Figure 1 is a diagrammatic view of a portion of a roundhouse equipped with a blow-off system embodying the features of the present invention;

Figure 2 is a detail view of the vented steam separator which enters into the organization of the system shown in Figure 1;

Figure 3 is a view in elevation of the blowoff pipe and its cold water connection forming a part of the system; and

Figure 4 is a sectional detail view of the ejector and backflow checking connection between the cold water pipe and the blowoff pipe.

Referring to Figure 1, A represents tracks

or stalls for locomotives arranged in annular series and in radial relation to a central turntable B. C represents a series of blow-off pipes each located between two tracks or stalls and in position to serve the stall on either side of it; and DD' represents the drain pipe which may lead through the outlet D² at the center of the turn table pit to the sewer connection D³. Interposed in the drainage system DD' is a steam separator E having a vent F which will permit the escape of steam entering thereinto in volume which would be objectionable in the sewer. As shown in Figure 2, the steam separating chamber E has in addition to its venting stack F an inlet pipe D and a discharge valve G having a manipulating connection H in controlling relation to the outlet D' by means of which the discharge of water and sludge from the blowoff products may be retarded until a sufficient proportion of the steam has been vented through the stack F to make it safe to discharge the products into the sewer.

Referring to Figure 3, the blowoff pipe C embodies in its construction a standpipe C' and a crane extension C² carrying at its outer end a flexible connector C³ through which it communicates with a boiler, as suggested for instance at X. The standpipe C' is swiveled to the blowoff pipe C at C⁴, its upper end being guided in a bearing C⁵, and this adapts the crane extension C² to swing from one position to another; for instance, to swing about the intermediate position C²⁰ of Figure 1 to the track A on either side of it and thus adapt each standpipe to serve two locomotives.

In order to condense steam to greatly reduce the violence of the discharge into the separating chamber E, a cold water pipe K is connected with the blowoff pipe C in such relation that the cold water delivered to the latter will condense steam coming off from the locomotive, and to render this more effective, such connection is made through the medium of an ejector K'. Such connection is also provided with the backflow check valve K² so that in the event of chokage or obstruction in the outlet of the blown-off products there will be no flow backward through the pipe K.

I claim:

1. In a blowoff system for steam boilers, a blowoff pipe, a drain receiving discharge

- therefrom, and a coldwater pipe delivering into said blowoff pipe, in relation to condense the steam flowing therethrough. 35
2. In a blowoff system for steam boilers, a blowoff pipe, a drain receiving discharge therefrom, and a coldwater pipe having an ejector connection through which it delivers into said blowoff pipe, in relation to condense the steam flowing therethrough. 40
- 10 3. In a blowoff system for steam boilers, a blowoff pipe, a drain receiving discharge therefrom, and a coldwater pipe having an ejecting and backflow checking connection through which it delivers into said blowoff pipe, in relation to condense the steam flowing therethrough. 45
- 15 4. In a blowoff system for steam boilers, a blowoff pipe, a drain receiving discharge therefrom, and a coldwater pipe delivering thereto, in relation to condense the steam flowing therethrough; said blowoff pipe including a standpipe and a crane extension through which it connects with the boiler. 50
- 20 5. In a blowoff system for steam boilers, a blowoff pipe, a drain receiving discharge therefrom, and a coldwater pipe delivering thereto, in relation to condense the steam flowing therethrough; said blowoff pipe including a standpipe and a crane extension through which it connects with the boiler; 55
- 25 said crane being adapted to swing to different positions for communication with different boilers. 60
- 30 6. A blowoff system for locomotives, comprising a plurality of locomotive stalls, a blowoff pipe located intermediately of said stalls and comprising a standpipe and a crane extension swiveling about the axis of the standpipe and adapted to make connection with a locomotive in either of said stalls, a drain receiving pipe receiving blowoff products from said standpipe, and a coldwater pipe delivering to said blowoff pipe in steam condensing relation thereto. 65
7. In a blowoff system for steam boilers, a blowoff pipe, a drain receiving dscharge therefrom, a coldwater pipe delivering into said blowoff pipe, in relation to condense the steam flowing therethrough, and a vented steam separating chamber interposed in said drain beyond the delivery point of said coldwater pipe. 70
8. In a locomotive roundhouse, stalls for locomotives, a drainage system for blowoff products including a vented steam separator, drainage pipes leading from a plurality of stalls to said separating chamber, standpipes located between stalls discharging into the respective drainage pipes, and having means for establishing blowoff connection with locomotives in the stalls, and coldwater standpipes connecting with the respective standpipes in relation to condense steam flowing therethrough. 75

Signed at Chicago, Illinois, this 31st day of January, 1921.

SPENCER OTIS.
